PRESSURE ACTUATED DELIVERY BOTTLE FOR LABORATORY USE

Joseph Kopp, Jackson Heights, N. Y.

Application November 23, 1954, Serial No. 33,207

Term of patent 14 years

(Cl. D16—2)

Fig. 1 is a side elevational view of a pressure actuated delivery bottle for laboratory use, showing my design.

Fig. 2 is a front elevational view of the same.

Fig. 3 is a plan view of the same.

Fig. 4 is a sectional view taken on the line 4-4 of Fig. 1.

I claim:

The ornamental design for a pressure actuated delivery bottle for laboratory use, as shown.
